CLAIM

The ornamental design for a side plate for an earth-working seed planting and fertilizing tool for an earth-working seed planting and fertilizing tool, as shown and described.

DESCRIPTION

FIG. 1 is a perspective view of a side plate for an earth-working seed planting and fertilizing tool showing my new design;

FIG. 2 is a left side elevational view thereof;

FIG. 3 is a right side elevational view thereof;

FIG. 4 is a top view thereof;

FIG. 5 is a bottom view thereof;

FIG. 6 is a rear elevational view thereof;

FIG. 7 is a front end elevational view thereof;

FIG. 8 is a perspective view of a second embodiment of FIG. 1;

FIG. 9 is a right side elevational view of FIG. 8;

FIG. 10 is a left side elevational view of FIG. 8;

FIG. 11 is a top view of FIG. 8;

FIG. 12 is a bottom view of FIG. 8;

FIG. 13 is a rear elevational view of FIG. 8; and,

FIG. 14 is a front elevational view of FIG. 8.
